RACKET STRINGING APPARATUS

Laurance C. Doll, Ithaca, N. Y., assignor to Doll
Air-Stringer of America, Inc., Ithaca, N. Y., a
corporation of New York

Application May 18, 1937, Serial No. 143,355

10 Claims. (Cl. 273—73)

This invention relates to certain new and useful improvements in racket stringing apparatus.

The primary object of the invention is to provide a racket stringing apparatus of the general type disclosed in the application for patent filed by Laurance C. Doll for improvements in Apparatus for stringing rackets, filed November 25, 1936, Serial Number 112,807, and more particularly relates to string gripping devices that are manually operated and placed for gripping engagement with the racket strings during the stringing of the racket for maintaining the strings under the tension imparted thereto during the stringing operation.

15 A further object of the invention is to provide racket stringing apparatus of the foregoing character wherein a pair of string gripping devices in the form of pivoted frames or lever members with a string gripping jaw at each end there-
20 of may be placed longitudinally or transversely of the racket frame with the gripping jaw at each end of the lever member selectively shifted into string gripping position adjacent the racket frame with means for holding the lever member against
25 pivotal or translating movement while a gripping jaw is engaged with a string.

With the above and other objects in view that will become apparent as the nature of the invention is better understood, the same consists in the 30 novel form, combination or arrangement of parts hereinafter more fully described, shown in the accompanying drawings and claimed.

In the drawings:—

Figure 1 is a side elevational view, partly 35 broken away and shown in section of a racket support for racket stringing apparatus and showing the pivoted frames or lever members carrying a gripping jaw at each end thereof with the lever members relatively positioned to place a 40 gripping jaw respectively at opposite ends of the two lever members in string gripping position with the other jaw carried by each member lowered to its inactive position, and further showing the pin and rack devices for holding the 45 lever members in adjusted positions;

Figure 2 is a top plan view of the string gripping members removed from the supporting frame;

Figure 3 is a cross-sectional view taken on line 50 3—3 of Figure 2 with a gripping jaw of each lever member shown by dotted lines in its elevated string gripping position;

Figure 4 is a detail sectional view taken on line 4—4 of Figure 2, showing the bearing for 55 the translating pivotal lever members;

Figure 5 is a detail sectional view taken on line 5—5 of Figure 4, showing the guide connection between the string gripping jaws;

Figure 6 is a detail sectional view taken on line 6—6 of Figure 3;

Figure 7 is a fragmentary elevational view of the supporting shaft and bearing for one of the lever members;

Figure 8 is an elevational view of one of the string gripping jaws, showing the file character- 10 istic of the string gripping face of the jaw;

Figure 9 is an edge elevational view of the gripping jaws shown in Figure 8; and

Figure 10 is a diagrammatic plan view of a racket frame with the gripping of the strings 15 indicated at certain points.

The support for the racket during the stringing operation is shown more clearly in Figure 1, wherein the reference character 10 designates a base plate adapted for mounting upon a frame 20 carrying the stringing apparatus for the racket, which structure is not illustrated as the present invention primarily relates to string gripping devices for holding the strings under tension placed thereon. A block support 11 rises from each end 25 of the base plate 10 and is longitudinally adjustable on the base plate in the guideways 12, the block supports 11 being retained in adjusted positions by the anchor devices 12a. Another block support 13 rises from each side of the base 30 plate 10 intermediate the ends of the latter and is shiftable transversely of the base plate into trans- 35 verse guideways 14, the block support 13 being suitably anchored in adjustable position.

Each of the block supports 11 and 13 carries 40 adjustable means for the support of a racket frame and as shown more clearly in Figure 1, each of the block supports has a horizontal opening 14 formed therein for sliding reception of a guide rod 15 that has a perpendicular plate 45 16 anchored at its lower end as at 17 to the inner end of the guide rod 15. A block 18 is secured as at 18a to the outer face of the upper end of the plate 16 and extends above the block support and said block 18 has a key groove there- 45 in that opens at the upper end of the block for interlocking reception of a key piece 19 from which racket engaging fingers 20 rise, the racket frame 21 being supported upon the upper ends of the blocks 18 outwardly of the pins 20 and 50 each of the blocks 18 is adapted to be adjusted to move the pins 20 into frictional retaining engagement with the inner face of the racket frame 21 as shown in Figure 1. The adjusting means for each block 18 includes a horizontally disposed 55

threaded shaft 22 resting upon the upper end of the associated block bearing 11 or 13, the inner end of the threaded shaft 22 being anchored as at 23 to the plate 16 directly beneath the racket frame supporting block 18. The threaded shaft 22 is adapted to be axially shifted for moving the blocks 18 relative to the racket frame 21 by means of a manually operated nut 24 threaded onto the shaft 22 and being substantially swiveled to the associated block support by means of the annular groove 25 in the collar of the nut 24 and into which groove a finger 26 carried by the block support extends so that upon rotation of the nut 24, the threaded shaft 22 is shifted axially to move the plate 16 carrying the block 18 that supports the racket frame 21, all of the parts being guided in their movements by the guide rods 15.

With the ratchet frame 21 supported upon the blocks 18 as shown in Figure 1, the same is in position to be strung by appropriate stringing devices such as disclosed in the application for patent of Laurance C. Doll, hereinbefore identified and during the stringing of the racket frame the string clamps or grips are adapted to be engaged with certain sections or runs of the string for holding the same under the tension imparted thereto. The string grip and supporting devices therefor include a shaft 27 having a manipulating handle 28 at one end thereof and said shaft 30 is adapted to be selectively mounted in horizontally aligned openings 29 in the opposed sets of block bearings 11 and 13 directly beneath the bearing openings 14 for the guide rods 15. A pair of lever members is translatable and pivotally supported on the shaft 27 and each lever member 30 carries a string gripping jaw 31 at its outer end.

A bearing is provided for each lever member 30 and as shown in Figure 4 includes a sleeve 32 slidable on the shaft 27 with a key 33 projecting inwardly of the bore of the sleeve 32 extending into a longitudinal key slot 34 provided in the shaft 27. An annular flange 35 is carried by the sleeve 32 adjacent one end thereof and said sleeve 32 has a lever member 30 supported thereon at one side of the annular flange 35 and as shown in Figures 3 and 4, the lever member 30 includes a pair of spaced parallel rods 36 and 37 connected at their outer ends by a head 38 for the support of a string gripping jaw 31. The rods 36 and 37 of the lever members 30 when horizontally disposed are freely slidable upon the sleeve 32 but when the lever member 30 is tilted or pivoted to assume the dotted line positions shown in Figure 3, the upper rack surface 39 of the lower rod 37 moves into engagement with an adjacent pin 40 that projects laterally of the flange 35 at each side of the shaft 27 to hold the lever member 30 against sliding or translating movement upon the bearing sleeve 32 and with the upwardly positioned gripping jaw 31 in position for engagement with the racket string at a point in proximity of the racket frame 21. The lever members 30 are retained in position on the sleeve 32 by means of the nut 41 threaded onto the threaded end of the sleeve 32 with a washer 42 interposed between the nut 41 and rods 36 and 37 of the lever member 30, the rods 36 and 37 being freely slidable upon the sleeve 32 and only restrained from such movement when the lever member is tilted to cause the rack teeth 39 upon the upper side of the lower bar to be engaged with a pin 40 carried by the flange 35.

The string gripping jaws 31 are supported

on the head 38 at the ends of the lever members 30, each head carrying a gripping jaw that includes a jaw member 43 that is carried by a shank 44 anchored as at 45 to one side of the head 38 with a movable jaw member 46 associated with the fixed jaw member 43. As shown in Figure 2, the shanks 44 carrying the gripping jaws at corresponding ends of the lever members 30 are respectively offset towards each other to present the gripping jaws at two corresponding ends of the lever members normally in closer relationship than the gripping jaws at the other two corresponding ends of the lever members. As shown in Figures 4 to 9, the lower straight edge of the movable jaw 46 is provided with three horizontally aligned transversely extending openings 47 that register with corresponding openings 47a in the fixed jaw 43, pins 48 anchored in the end openings 47 of the movable jaw 46 projecting therefrom for guiding reception in the end openings 47a in the fixed jaw. A headed screw 49 passes through the central opening 47a in the fixed jaw and is threaded into the registering central opening 47 in the movable jaw, this arrangement being shown in Figure 5. Opposed sockets 49 and 49a are formed in the inner faces of the jaws 43 and 46 for the reception of a coil spring 50 that normally tends to separate the jaws. The opposed faces of the upper ends of the jaws 43 and 46 carry file plates 51 to effect proper gripping of the racket strings and the terminal upper horizontal edges of the two jaws 43 and 46 are transversely notched as at 52 to provide clearance for strings extending transversely of the longitudinal axis of a string gripping jaw, the notches 52 being spaced apart a distance corresponding to the distance between the racket strings. Each of the jaws 43 and 46 is provided with an aligned transverse opening 53 directly above the socket 49, the opening 53 in the jaw 43 being threaded for engagement by the jaw operating screw 54 that freely extends through the opening 53 in the movable jaw 46, the outer end of the screw 54 carrying a disk head 55 that is movable into engagement with the jaw 46 for moving the same into clamping engagement with the fixed jaw 43, the terminal outer end of the screw 54 outwardly of the disk head 55 carrying an operating handle 56.

The shaft 27 supporting the lever members 30 is illustrated in Figure 1 as mounted in the block support 13 for cooperation with the longitudinal strings of the racket, it being understood that the shaft 27 is also adapted to be positioned in the bearings 29 in the block supports 11 for gripping engagement with the transverse strings of the racket. In the stringing of a racket, the lever members 30 are shifted to the positions shown in Figure 1 and are locked in such positions by the engagement of the rack portion 39 of the lower rod 37 of a lever member engaged with a pin 40 and when so disposed, the gripping jaw at one end of a lever member is elevated to string gripping position while the jaw member upon the same frame lever member is lowered to its inoperative position, the stringing of the racket beginning at the median line thereof with the lever members being sequentially moved outwardly or separated from each other on the supporting shaft 27 for gripping engagement with the subsequent string to be extended. The stringing of the racket frame is schematically illustrated in Figure 10, the gripping jaw at one end of a lever member being initially engaged with the string a at the point b while a pulling force is exerted

on the string *c* in the direction of the associated arrow line outwardly of the opposite end of the racket frame. The string gripping jaw of the other lever member is then engaged with the end 5 of the string *c* at the point *d*, with the string *c* being then tensioned between the points *b* and *d*. The second pulling strain is placed on the 10 string *a* outwardly of the bracket frame while the gripping jaw is still engaged with the string *a* at the point *b* and after the string *a* has been placed under the desired tension, a gripping jaw is engaged with the opposite end of the string *a* at the 15 point *e*, the gripping jaw being disengaged at the point *b* so that both strings *a* and *b* are then fully tensioned between the points *b* and *d*. The third pull is exerted upon the string *f* outwardly of the 20 racket frame and a gripping jaw engaged therewith at the point *g*, while the fourth pull is exerted upon the string *i* outwardly of the racket frame 25 and gripping jaw engaged therewith at the point *k*, this operation being continued until the racket frame is completely strung in one direction and after which the gripping jaws are shifted for engagement with the strings that extend trans- versely of the racket frame 21.

From the above detailed description of the invention, it is believed that the construction and operation thereof will at once be apparent and while there is herein shown and described the 30 preferred embodiment of the invention, it is nevertheless to be understood that minor changes may be made therein without departing from the spirit and scope of the invention as claimed.

I claim:—

35 1. In racket stringing apparatus, a base plate, two pairs of diametrically opposite block supports respectively attached to the side and end portions of the base plate for the mounting of racket frame supports, means for gripping the 40 racket strings for holding them under tension during the stringing of the racket frame including a shaft selectively mounted in a pair of diametrically opposite supports, and a pair of elements having translatable pivotal mountings on the 45 shaft intermediate the ends thereof whereby said elements may be moved both longitudinally and laterally of the shaft into string gripping position for gripping engagement with a racket string.

50 2. In racket stringing apparatus, a base plate, two pairs of diametrically opposite block supports respectively attached to the side and end portions of the base plate for the mounting of racket frame supports, means for gripping the 55 racket strings for holding them under tension during the stringing of the racket frame including a shaft selectively mounted in a pair of diametrically opposite supports, and a pair of elements having translatable pivotal mountings on the 60 shaft intermediate the ends thereof whereby said elements may be moved both longitudinally and laterally of the shaft into string gripping positions and a string gripping jaw at each end of said elements adapted for gripping 65 engagement with a racket string.

3. In racket stringing apparatus, a base plate, two pairs of diametrically opposite block supports respectively attached to the side and end portions of the base plate for the mounting of 70 racket frame supports, means for gripping the racket strings for holding them under tension during the stringing of the racket frame including a shaft selectively mounted in a pair of diametrically opposite supports, a pair of elements having translatable pivotal mountings on the 75

the shaft intermediate the ends thereof whereby said elements may be moved both longitudinally and laterally of the shaft into string gripping positions for gripping engagement with a racket string, and cooperating means carried by said elements and shaft for holding the elements in shifted positions. 5

4. In racket stringing apparatus, a base plate, two pairs of diametrically opposite block supports respectively attached to the side and end 10 portions of the base plate for the mounting of racket frame supports, means for gripping the racket strings for holding them under tension during the stringing of the racket frame including a shaft selectively mounted in a pair of diametrically opposite supports, a pair of elements having translatable and pivotal mountings on the shaft whereby said elements may be moved both longitudinally and laterally of the shaft into spring gripping positions, a string gripping 15 jaw at each end of said elements adapted for gripping engagement with a racket string, and cooperating means carried by said elements and shaft for holding the elements in shifted positions. 20

5. In racket stringing apparatus, a base plate, two pairs of diametrically opposite block supports respectively attached to the side and end portions of the base plate for the mounting of racket frame supports, means for gripping the racket strings for holding them under tension during the stringing of the racket frame including a shaft selectively mounted in a pair of diametrically opposite supports, a pair of elements having translatable pivotal mountings on the shaft whereby said elements may be moved both longitudinally and laterally of the shaft into string gripping positions, each element including 30 a lever member having a pair of spaced parallel rods, a head connecting corresponding ends of the rods, a string gripping jaw carried by each head and cooperating means carried by one of said rods and said shaft for holding the elements in shifted positions. 35

6. In racket stringing apparatus, a base plate, two pairs of diametrically opposite block supports respectively attached to the side and end portions of the base plate for the mounting of racket frame supports, means for gripping the racket strings for holding them under tension during the stringing of the racket frame including a shaft selectively mounted in a pair of diametrically opposite supports, a pair of elements having translatable pivotal mountings on the shaft whereby said elements may be moved both longitudinally and laterally of the shaft into string gripping positions, each element including a 40 lever member having a pair of spaced parallel rods, a head connecting corresponding ends of the rods, a string gripping jaw carried by each head and cooperating means carried by one of said rods and said shaft for holding the elements in shifted positions. 45

7. In racket stringing apparatus, a base plate, two pairs of diametrically opposite block supports respectively attached to the side and end portions of the base plate for the mounting of racket frame supports, means for gripping the racket strings for holding them under tension during the stringing of the racket frame including a shaft selectively mounted in a pair of diametrically opposite supports, a pair of elements having translatable pivotal mountings on the shaft whereby said elements may be moved both longitudinally and laterally of the shaft into string gripping positions, each element including a lever member having a pair of spaced parallel rods, a head connecting corresponding ends of the rods, a string gripping jaw carried by each head and cooperating means carried by one of said rods and said shaft for holding the elements in shifted positions including a bearing on the shaft for said element, pins projecting from said bearing at opposite sides of said shaft and rack teeth on the inner side of one of the rods adapted for engagement with a pin when said element is pivotally moved to place one of the jaws in string gripping position. 55

8. In racket stringing apparatus, a base plate, two pairs of diametrically opposite block supports respectively attached to the side and end portions of the base plate for the mounting of racket frame supports, means for gripping the racket strings for holding them under tension 70

during the stringing of the racket frame including a shaft selectively mounted in a pair of diametrically opposite supports, a pair of elements having translatable pivotal mountings on the 5 shaft whereby said elements may be moved both longitudinally and laterally of the shaft into string gripping positions, a string gripping jaw at each end of said elements for gripping engagement with a racket string, and cooperat- 10 ing means carried by said elements and shaft for holding the elements in shifted positions, each gripping jaw including a jaw member fixed to the pivotal element, a jaw movable relative to the fixed jaw and string engaging file plates se- 15 cured to the active faces of the fixed and movable jaws, and both of said jaws of a pivotal element being normally disposed in a plane below the plane of the racket frame to be strung with the jaws at each end selectively raised into 20 position for string gripping activity.

8. In racket stringing apparatus, a base plate, two pairs of diametrically opposite block supports respectively attached to the side and end portions of the base plate for the mounting of 25 racket frame supports, means for gripping the racket strings for holding them under tension during the stringing of the racket frame includ- 30 ing a shaft selectively mounted in a pair of diametrically opposite supports, a pair of ele- 35 ments having translatable pivotal mountings on the shaft whereby said elements may be moved both longitudinally and laterally of the shaft into string gripping positions and a string gripping jaw at each end of said elements adapted for 40 gripping engagement with a racket string, and cooperat- 45 ing means carried by said elements and shaft for holding the elements in shifted positions, each gripping jaw including a jaw mem- 50 ber fixed to the pivotal element, a jaw movable relative to the fixed jaw, and both of said jaws of a pivotal element being normally disposed in a plane below the plane of the racket frame to be strung with the jaws at each end selectively raised into position for string gripping activity.

9. In racket stringing apparatus, a base plate, two pairs of diametrically opposite block supports respectively attached to the side and end portions of the base plate for the mounting of racket frame supports, means for gripping the racket strings for holding them under tension during the stringing of the racket frame includ- 55 ing a shaft selectively mounted in a pair of diametrically opposite supports, a pair of elements having translatable pivotal mountings on the 60 shaft whereby said elements may be moved both longitudinally and laterally of the shaft into string gripping positions, a string gripping jaw at each end of said elements for gripping engagement with a racket string, and cooperat- 65 ing means carried by said elements and shaft for holding the elements in shifted positions, each gripping jaw including a jaw member fixed to the pivotal element, a jaw movable relative to the fixed jaw and string engaging file plates secured to the active faces of the fixed and movable jaws, and both of said jaws of a pivotal element being normally disposed in a plane below the plane of the racket frame to be strung with the jaws at each end selectively raised into position for string gripping 70 activity.

10. In racket stringing apparatus, a base plate, two pairs of diametrically opposite block supports respectively attached to the side and end portions of the base plate for the mounting of racket frame supports, means for gripping the racket strings for holding them under tension during the stringing of the racket frame includ- 75 ing a shaft selectively mounted in a pair of diametrically opposite supports, a pair of elements having translatable pivotal mountings on the 80 shaft whereby said elements may be moved both longitudinally and laterally of the shaft into string gripping positions, a string gripping jaw at each end of said elements for gripping engagement with a racket string, and cooperat- 85 ing means carried by said elements and shaft for holding the elements in shifted positions, each gripping jaw including a jaw member fixed to the pivotal element, a jaw movable relative to the fixed jaw and string engaging file plates secured to the active faces of the fixed and movable jaws, and both of said jaws of a pivotal element being normally disposed in a plane below the plane of the racket frame to be strung with the jaws at each end selectively raised into position for string gripping 90 activity.

LAURANCE C. DOLL.
